UNITED STATES PATENT OFFICE.

SIDNEY RICHARDSON MORRIS MALLOCH, OF PHILADELPHIA, PENNSYLVANIA.

SILENT RAILWAY-CROSSING.

1,249,981.

Specification of Letters Patent. Patented Dec. 11, 1917.

Application filed March 9, 1917. Serial No. 153,648.

To all whom it may concern:

Be it known that I, SIDNEY RICHARDSON MORRIS MALLOCH, a citizen of the United States, residing at Philadelphia, in the 5 county of Philadelphia and State of Pennsylvania, have invented certain useful Improvements in Silent Railway-Crossings, of which the following is a specification, reference being had therein to the accompanying 10 drawing.

The present invention has reference generally to improvements in that class of inventions known as rails and rail joints and more particularly relates to a railway crossing especially, though not necessarily, adapted 15 for street cars.

It is the principal aim and object of the present invention to provide a crossing of such construction that when the rolling stock 20 passes thereover, the action thereof will be silent, thus obviating jars, shocks and other noises usually incident to devices of this character.

It is an additional and equally important 25 object of the present invention to provide a crossing insert cast in a single piece for engagement with the correspondingly formed portions of a track crossing consisting of intersecting rails constructed so that the insert 30 may be readily fitted thereover.

More particularly, the present invention includes the provision of novel means formed 35 in the grooves in the rail head sections forming the insert for preventing the tread portions of the wheels of the rolling stock from striking the edges of the tread surfaces of the rail head sections at the intersections thereof, said means being designed so as to be engaged by the flanges of the wheels for 40 supporting such tread portions without raising the tread portions of the wheels, thus permitting of the rolling stock to pass over the crossing without danger of jumping the track or causing any other damage and allowing 45 the rolling stock to pass over the crossing without a slackening of the speed thereof.

The invention as a further improvement resides in the provision of novel means for 50 fastening the crossing insert to the crossing of the main track,

Among the other aims and objects of this invention may be recited the provision of a device of the character mentioned, with a view to compactness, and in which the number of parts are few, the construction simple, the cost of production low and the efficiency high.

Other objects as well as the nature, characteristic features and scope of this invention will be more readily apparent from the following description taken in connection with the accompanying drawings, and pointed out in the claims, forming a part of this specification.

The invention is clearly illustrated in the accompanying drawings, in which:

Figure 1 is a top plan view thereof.

Fig. 2 is a section taken on line 2--2 of Fig. 1.

Fig. 3 is another section taken on line 3--3 of Fig. 1.

Fig. 4 is a fragmentary perspective of the invention.

Fig. 5 is an enlarged transverse section taken on line 5--5 of Fig. 1, a portion of the wheel of the rolling stock being indicated.

Fig. 6 is an enlarged transverse section taken on line 6--6 of Fig. 1, a portion of the wheel of the rolling stock being indicated.

Similar characters of reference are employed in all of the above described views, to indicate corresponding parts.

Referring now, more particularly, to the accompanying drawings there is provided a crossing of the main track consisting of pairs of intersecting rails 1 and 2 having the head portions removed leaving only the webs as indicated by the numeral 3 and forming shoulders 4.

As intimated, a crossing insert has been provided which in the present instance consists of pairs of rail head sections 5 and 6 which intersect each other being cast in one piece embodying preferably tread portions 7 having offset flanges 8 on their adjacent inner surfaces providing arched bottom grooves 9 therebetween.

With a view toward providing suitable means for removably securing the insert in position spaced parallel wings 10 depend-

from the respective ends of the head sections and also depending from the under surface at points substantially intermediate the ends thereof are other similarly formed spaced 5 wings 11. The wings 10 and 11 are straddled about the web portions 3 of the main track crossing so that the under surfaces of the head sections rest upon the upper surfaces of the web portions, engagement being 10 effected by bolts 12 which extend transversely through the registering openings and have their free ends engaged by nuts 13 for clamping the parts in the position shown in Fig. 1. It will be noted that the ends of 15 the head sections are of such length that they abut the shoulders 4, this arrangement being illustrated in Fig. 2, consequently arranging the head sections 5 and 6 flush with the head or tread portions of the rails 1 20 and 2.

With a view toward obviating the noise usually occasioned when rolling stock passes over a crossing, ribs 14 are formed integral with the bottoms of the grooves and preferably have their upper surface arched and extend through the portions of the head sections and also a distance beyond these points. The respective terminals of the ribs beyond 25 the points of intersection are gradually inclined downwardly so as to meet the bottoms of the grooves. Obviously the ribs are the width of the grooves and in effect are substantially raised portions, having a height equivalent to the usual space between the 30 flange portions 16 of the wheels of the rolling stock and the bottom of the grooves 9, consequently preventing the tread portions 17 from engaging and knocking the intersecting head sections which extend across 35 the head sections upon which the rolling stock is traveling. In other words the relation of the parts is such that the tread portion will be supported by the flange portions when passing over a crossing and this 40 is due to the fact that the depth from the tread portions on the rails to the upper surface of the inserts is similar to the depth of the wheel flanges. Obviously in cases of 45 false flanges on the wheels the inclined surfaces 15 of the ribs cause the flanges 16 to gradually engage the ribs as the rolling stock approaches the intersection of the head sections without raising the tread portions 17, allowing the wheels to pass readily and 50 noiselessly over the intersecting head sections without danger of jumping. Because of this incline it will also be appreciated that the motorman is not inconvenienced by slackening the speed of the street car or other 55 vehicle for the same to pass over the crossing at a relatively high rate of speed. It may be understood, however, that by providing the insert in combination with the cross-

ing of the main track, an efficient and operable railway crossing is provided whereby 65 practically all noise and jarring is obviated when rolling stock passes thereover.

In view of the foregoing remarks it is believed that a detailed description of the operation is unnecessary. Likewise it is believed 70 that the advantages of the invention will be readily apparent.

It will be understood that the foregoing description and accompanying drawings comprehend only the general and preferred 75 embodiment of this invention and that various minor changes in detail of construction, proportion and arrangement of the parts may be made within the scope of the appended claims and without sacrificing any 80 of the advantages of this invention.

Having thus fully described the invention, what is claimed is:

1. In a railway crossing, in combination with a crossing of the main track consisting 85 of intersecting rail sections having the head portions removed providing shoulders beyond the points of intersection, a crossing insert cast in a single piece and consisting of intersecting rail head sections, tread portions formed on their upper surfaces adjacent their outer sides, flanges offset on the adjacent inner surfaces and providing grooves therebetween which also intersect each other, means for removably yet rigidly 90 connecting the head sections forming the insert to the main sections of the track so that the ends of the end sections abut the shoulders and lie flush with the main track, and means formed integral with the bottom of 100 the grooves and extending throughout the portions intermediate the points of intersection of the head sections and also a distance beyond these points thereby to support the flange portions of the wheels of the rolling 105 stock without raising the tread portions of the wheel as the rolling stock passes over the intersections.

2. In a railway crossing, in combination with a crossing of the main track consisting 110 of intersecting rail sections having the head portions removed providing shoulders beyond the points of intersection, a crossing insert cast in a single piece and consisting of intersecting rail head sections, tread portions formed on their upper surfaces adjacent 115 their outer sides, flanges offset on the adjacent inner surfaces and providing grooves therebetween which also intersect each other, spaced parallel wings integral 120 with and depending from the under surfaces of the head sections for straddled engagement with the web portions of the main rails left when the head portions are removed to permit of the head sections to rest on the 125 web portions of the main rails, means for re-

movably yet rigidly securing the wings and web portions of the main rails together so that the ends of the head sections abut the shoulders of the main rail sections, and ribs 5 formed integral with the bottom of the grooves and extending throughout the portions of the head sections intermediate the points of intersection thereof and also a distance beyond these points and having the respective terminals gradually inclined 10 downwardly to meet the bottoms of the grooves.

In testimony whereof I affix my signature.
SIDNEY RICHARDSON MORRIS MALLOCHE.
